COACH BODY FOR PICK-UP TRUCKS

Robert K. Osburn, 7015 192nd Place SW., Lynnwood,
Wash., and Wilson E. Kumba, Bothell, Wash.; said
Kumba assignor to said Osburn

Filed Apr. 27, 1962, Ser. No. 69,876

Term of patent 14 years

(Cl. D14—3)

FIG 2

FIG 3

FIG 4

FIGURE 1 is a rear perspective view of a coach body for pick-up trucks, showing our new design;

FIGURE 2 is a front perspective view thereof on a reduced scale;

FIGURE 3 is a side elevational view thereof; and

FIGURE 4 is an enlarged sectional view taken on the lines 4-4 of FIGURE 1.

The truck shown in broken lines in FIGURES 1 and 2 is included for illustrative purposes only.

We claim:

The ornamental design for a coach body for pick-up trucks, as shown and described.
